UNITED STATES PATENT OFFICE.

DILLARD A. WHITAKER AND HARRY W. THAYER, OF SACRAMENTO, CALIFORNIA.

LIFE-BOAT.

1,273,298.

Specification of Letters Patent. Patented July 23, 1918.

Application filed January 2, 1917. Serial No. 140,084.

To all whom it may concern:

Be it known that we, DILLARD A. WHITAKER and HARRY W. THAYER, citizens of the United States, residing at Sacramento, in 5 the county of Sacramento and State of California, have invented new and useful Improvements in Life-Boats, of which the following is a specification.

This invention relates to life boats; and 10 has for its object to provide a safe and substantial structure that will afford security to the occupants in any emergency and capable of being launched in any condition of sea.

Generally stated, the boat comprises an 15 inclosed water-tight structure capable of being submerged to great depths without danger of collapse or leakage, and so shaped and constructed as to float upon its sides or 20 top when for any reason it should be overturned in launching and gradually assume an upright keel thereafter.

In many marine disasters, such as in the 25 case of the "Lusitania", the vessel sinks so suddenly as to afford no time for launching the usual life boat and rowing it away from danger by the sinking vessel. The sinking of the vessel creates a suction or swirl which tends strongly to draw the life boats down 30 with it. In the present device, by reason of the inclosed structure and the arrangement of longitudinal beams or keels upon the sides and top thereof, as well as on the bottom, the life boat, after the occupants are once 35 in place and the hatches closed, will be safe in any emergency whether it be overturned or submerged by the suction of the sinking vessel. Preferably we construct the boat of large size and equip the same with power 40 propelling mechanism and steering apparatus so that the boat may be driven to shelter in case of a mid-ocean accident.

One form which our invention may assume is exemplified in the following description 45 and illustrated in the accompanying drawings, in which—

Figures 1 and 2 show diagrammatic views of a device embodying our invention.

Fig. 3 shows a side elevation of the same. 50 Fig. 4 shows a front elevation.
Fig. 5 shows a rear elevation.
Fig. 6 shows a plan view of said boat.
Fig. 7 shows a longitudinal, vertical, sectional view of the same.
55 Fig. 8 shows a cross sectional view, taken on the line *a—a* of Fig. 7.

In the drawings, we show an inclosed boat, whale back in shape, or, more particularly, substantially elliptical in cross section, the bow and stern being rounded. The 60 boat comprises a hull having a skeleton or frame of steel which includes top and bottom keels 1 and side keels 2, preferably T-shaped in cross section. These keels are shown as spaced substantially 90° apart and 65 are united at their ends forming a rounded bow and stern of the boat. Transverse ribs 2^a continuous and in the shape of an ellipse are included in the frame construction and 70 wooden strakes 21, carried by said ribs, extend continuously fore and aft of the frame for stiffening the hull longitudinally.

The shell of the boat is formed by steel 75 plates 25 inclosing the top, bottom and sides and riveted in place upon the steel frame; suitable portholes 5 and hatchways 3 being 80 formed in the shell and made water-tight, whereby to form an inclosed structure capable of being submerged to great depths and so supported and reinforced throughout 85 as to withstand the local strains upon the top and sides incident to capsizing or overturning. The hull is provided within with center posts 22 extending vertically between the top and bottom keels and flooring 20. Seats 19 having compartments 23 beneath for ballast or water, together with other compartments 21 for provisions, may 85 be included in the interior construction.

The hatchways 3 are provided with eyes 90 for engagement by the long-shanked hooks 6 to hold the same opened, said hooks extending from opposite sides of the top keel 1. On the under side of the side keels the 95 rope rails 8 are securely held by the eye bolts 13.

A motor is shown at 14 for operating a propeller 7 by means of a shaft 16 extending through the floor, which latter is upwardly inclined at the stern of the boat and supported upon a false keel 10, through which the shaft 16 also extends. The keel 10 is cut away at the rear to receive the propeller 7 and a rudder 11, the latter being operated by suitable connection 17 extending to a 100 pilot wheel 18 at the front of the boat. The top keel 1 is provided with eyes 12 and 24 to receive davit hooks, by means of which the life boat is carried and launched in the usual way.

The bottom portion of the boat is made 110 slightly longer transversely than the top

and by reason of this, coupled with the fact that suitable ballast will be stored in the bottom, the boat even if launched in an overturned position will gradually assume an upright keel. The provision of the side and top keels will afford sufficient strength and reinforcement for the hull in case the boat is overturned and the rounded ends whereby the four keels may be joined together at their ends, together with the other reinforcement, including the longitudinally extending members 21, will provide ample support for the hull no matter how excessive the strains may be which are imposed upon any portion of the boat. Also a boat so constructed may be submerged to great depths without danger of collapse. There is no water line as such and the boat may, therefore, be loaded beyond the usual capacity of vessels of this size without danger.

By reason of the inclosed water-tight construction and the provision of power-propelling and steering mechanism the boat may be operated in any kind of a sea and for a considerable distance, provision being made for storage of supplies and compressed air whereby to sustain life.

Figs. 1 and 2 are projection views, the lines and numbers identifying corresponding points on the hull in both views.

Various changes in the construction and arrangement of the several parts herein shown and described may be employed with-

out departing from the spirit of our invention as disclosed in the appended claim. 35

Having thus described our invention, what we claim and desire to secure by Letters Patent is—

A life boat comprising a hull of substantially elliptical form, a longitudinal T-shaped keel beam extending about the hull and having its cross top portion secured thereto so that its vertical web will extend outwardly therefrom the bottom of the hull having its rear part raised off the keel beam in an upwardly and rearward direction so as to space the cross top portion of said beam from the hull, a sheet-like false keel interposed between the raised part of the hull and the keel beam and secured to the cross top portion of the latter, said false keel being cut away to provide an opening for a propeller and rudder above the keel beam, a propeller and a rudder both arranged in the opening of the false keel, the cross top portion of the keel beam extending from opposite sides of the false keel to reinforce the same and to afford protection to the propeller and rudder.

In testimony whereof we have hereunto set our hands in the presence of the subscribing witness.

DILLARD A. WHITAKER.
HARRY W. THAYER.
